UNITED STATES PATENT OFFICE.

R. C. JACKSON, OF DETROIT, MICHIGAN.

IMPROVEMENT IN VAPOR AND COAL-OIL FURNACES

Specification forming part of Letters Patent No. 44,097, dated September 6, 1854.

To all whom it may concern:

Be it known that I, R. C. JACKSON, of Detroit, in the county of Wayne and State of Michigan, have invented a new and Improved Apparatus for Burning Petroleum, Coal-Oil, &c.; and I do hereby declare that the following is a full and complete description of the construction and operation of the same, reference being had to the accompanying drawings, making a part of this specification, in which—

Figure 1 is a top view of the fire-box with the crown-sheet removed, and the deflectors partly broken away to show the pipes. Fig. 2 is a vertical section of the fire-box in the direction of the line *x x* in Fig. 1. Fig. 3 is a sectional view in the direction of the lines *y y* in Fig. 1.

Similar letters of reference indicate like parts in the several views.

The nature of my invention relates to an apparatus for burning petroleum, coal-oil, naphtha, &c., as fuel, in the consumption of which a gas is generated and burned.

In the different figures, A represents the fire-box; B, the water-space between the outside and inside sheetings, *a b*, designed to be connected with a boiler in any desired manner. Along the fire-box, underneath the boiler, are arranged deflectors and heaters C, that are supported at each end by the pieces or supports E and D, cut out at the top, so that the deflectors fit into the notches, and there are plates, *m n*, above to keep them down in place. These deflectors are V-shaped, as represented in Fig. 2, widening out toward the top. The edges of the different deflectors come together at the top, so as to leave a small space or opening, *b'*, between them. Along directly under these openings are the pipes or tubes F, which are supported at one end by the piece D, being curved out between the deflectors, where the pipes come, as represented in Fig. 2. The other ends of these pipes enter the pipe G at that end of the fire-box. The pipe G has a cap, *g*, screwed onto each end, rendering it perfectly close at the ends. It is kept in place by the support E, that extends under the pipe and up on one side, as represented in Fig. 3. This support is secured at each end to the sides of the fire-box, as shown at *h* in Fig. 1, supporting the pipe, and also the deflectors at that end of the fire-box.

In the water-space at one end is the tube or screw I, through which the tube or end of the siphon H passes, and is secured as it enters the pipe G at the center. The tube H curves down outside of the fire-box in the form of an inverted siphon, as seen in Fig. 3, through which the oil is conveyed from the reservoir into the fire-box, K being a cock or faucet to gage the quantity of oil discharged from the reservoir into the pipes. The oil coming from the reservoir through the siphon flows into the pipe G, runs along this pipe, and is distributed into the different pipes F, which are heated by means of temporarily heating the end of one or more of the pipes, thereby heating the oil and generating gas, which passes up through the gas-holes *d* and burns, as represented at *f* in Fig. 2, the flames issuing through the openings *b'* between the deflectors. The pipes are so connected that as one becomes heated and generates gas the heat is rapidly conveyed to all the other pipes, and the heat from the burning gas issuing from the holes *d* is communicated to the pipes, thereby causing them constantly to generate gas, and they become in this way self-generators. The heaters and deflectors C, from their peculiar shape and arrangement in connection with the pipes, concentrate and intensify the heat produced by the combustion of the oil. They confine the heat around the pipes or flues F, causing a rapid generation of gas, which produces the desired amount of heat for any purpose for which it may be designed.

One object of having the oil conveyed into fire box through a tube curved in the form of an inverted siphon is to prevent the gas, under any circumstance, from passing back into the reservoir, which prevents all danger of explosion.

It is found by experience that gas is generated more rapidly in the pipes when they are only about half-full of naphtha or oil, and in order to prevent too much oil running into the pipes F from the pipe G a plug, *k*, with a hole through the center, is put in the end of each pipe, where it enters the pipe G, the oil running through the holes in the plugs into the pipes in a sufficient quantity to produce the most perfect combustion. There are plugs, *e*, in the other end of the pipes, which can be

removed for the purpose of cleaning out the pipes when it is necessary, and the caps *g* on the ends of the pipe *G* can be taken off for the same purpose.

What I claim as my improvement, and desire to secure by Letters Patent, is—

The pipes *F* and *G*, in combination with the

deflectors *C*, when arranged and operating conjointly in the manner and for the purpose set forth.

R. C. JACKSON.
